CLAIM

The ornamental design for a conductor in a radio frequency identification tag antenna assembly, as shown and described.

DESCRIPTION

The present application may also be considered to be related to co-pending U.S. Design patent application Ser. No. 29/220, 504 filed Dec. 30, 2004, in the name of inventor Ronald A. Oliver, entitled “Radio Frequency Identification Tag Antenna Assembly”, commonly owned herewith.

The present application may also be considered to be related to co-pending U.S. Design patent application Ser. No. 29/220, 493 filed Dec. 30, 2004, in the name of inventor Ronald A. Oliver, entitled “Radio Frequency Identification Tag Antenna Assembly”, commonly owned herewith.

FIG. 1 is a top plan view of a radio frequency identification tag antenna assembly showing our new design, the bottom being flat;

FIG. 2 is a left side elevation view thereof, the right side elevation view being a mirror image thereof;

FIG. 3 is a front elevation view thereof, the rear elevation view being a mirror image thereof; and,

FIG. 4 is a front perspective view thereof.

It is certified that error appears in the above-identified patent and that said Letters Patent is hereby corrected as shown below:

Title page item [54] and Col. 1, line 5 delete title “RADIO FREQUENCY IDENTIFICATION TAG ANTENNA ASSEMBLY” and insert --CONDUCTOR FOR RADIO FREQUENCY IDENTIFICATION TAG ANTENNA ASSEMBLY--.

Please delete “Embeded” after “Raszka et al.” on page 2, column 2, in section “OTHER PUBLICATIONS” and insert --Embedded--.

Please delete “Privocy” after “Aims to Soothe” on page 2, column 2, in section “OTHER PUBLICATIONS” and insert --Privacy--.
